CLAIM

The ornamental design for a mascara case, as shown and described.

DESCRIPTION

FIG. 1 is a top perspective view of a mascara case showing my new design;

FIG. 2 is a top plan view thereof, the bottom plan view being a mirror image of the top plan view;

FIG. 3 is a side elevational view of FIG. 2, the side opposite being a mirror image thereof;

FIG. 4 is a left end view of FIG. 3; and,

FIG. 5 is a right end view of FIG. 3.
